UNITED STATES PATENT OFFICE

ARTHUR M. ACHESON, OF DOBBS FERRY, NEW YORK, ASSIGNOR TO DURIUM PRODUCTS CORPORATION, OF NEW YORK, N. Y., A CORPORATION OF DELAWARE

PHONOGRAPH RECORD

Application filed October 10, 1930. Serial No. 487,713.

The present invention relates broadly to phonograph records, and more especially to a record table pin holder for a flexible phonograph record.

5 Flexible phonograph records made on a paper stock of substantially cardboard thickness may have a tendency in repeated use to enlarge the record table pin opening due to wear, so that the record may leave the record 53 turntable while the record is being played.

10 The present invention overcomes the difficulties above outlined by providing friction members passing through the pin opening in the record and being adapted to engage with 58 the sides of the pin on the record table of a phonograph.

15 The present invention in its preferred form comprises the interlacing of a live rubber band through the phonograph record 63 adjacent the pin opening in such manner that the record table pin engages with the rubber bands, thereby relieving the sides of the pin opening of the friction necessary to hold the record in position on the record turntable. 68 20 The rubber bands may either pass through the pin opening or be arranged in such manner that a portion of the rubber bands extend across the said opening so that the rubber bands form the major contact with the sides 73 of the pin to hold the record in place on the 78 table.

25 It is to be understood that the present invention may be practiced in constructions differing from the disclosure herewith and, 83 therefore, the said disclosure is to be considered as illustrative and not in the limiting 88 sense.

30 Fig. 1 illustrates a plan view of the preferred form of the present invention.

35 Fig. 2 is an enlarged sectional view on lines 2-2 of Fig. 1.

40 Fig. 3 is a plan view of a modified form of the invention.

45 Fig. 4 is an enlarged sectional view on lines 4-4 of Fig. 2.

50 Fig. 5 is a plan view of a further modification of the present invention.

Fig. 6 is an enlarged view on lines 6-6 55 of Fig. 5.

Fig. 7 is a plan view of another modification of the present invention.

Fig. 8 is an enlarged sectional view on lines 8-8 of Fig. 7.

55 Referring now to the drawings and more especially to Figs. 1 and 2, a flexible phonograph record body 1 is provided with a pin opening 2. A plurality of openings 4 are provided around the pin opening 2 and a rubber band 5 of resilient live rubber is laced 60 through the pin opening 2 and the several openings 4 in such manner as to provide portions 6 of the bands extending through said pin opening and forming substantially a live rubber wall in the pin opening so that 65 when a record table pin 7 (indicated in dotted lines in Fig. 2) is forced through the pin opening 2, these rubber bands are slightly compressed so as to form friction members 70 engaging the side walls of the pin 7 which thereby holds the record flat on the table without any danger of the record tending to ride up over the pin 7. Repeated use of the record brings the wear from the pin on the portions of the rubber band 6 75 which have a relatively long life and consequently, the record may be used for a very long period of time without substantial enlargement of the pin opening, and in this way effectually hold the record in position 80 while it is being played.

78 Figs. 3 and 4 illustrate a modification of the invention in which individual sections 8 of rubber bands are locked in position to extend through the pin opening 2 by forcing one end 9 of the rubber bands through a narrow slit in the record body and forcing the other end 10 of the rubber bands through an adjacent narrow slit, thereby forming a 85 loop 11, a portion of which extends through the pin opening in such manner as to provide portions 12 which preferably are located 120° apart around the pin opening to engage the sides of the pin. The slits in the record body are preferably less in width than the thickness of the band so that after the ends have been forced through the slits the expansion of the rubber anchors the ends in place.

88 Figs. 5 and 6 illustrate another form of the invention in which rubber bands 14 ex- 90

tend through openings 15 to form a triangular figure on both sides of the record with the sides 16 of the triangle slightly overlapping the pin opening 2, so that when the record is placed in position on the pin, these side members 16 of the rubber band embrace the record pin and form friction members to hold the record in position on the turntable of the phonograph.

10 Figs. 7 and 8 show a further modification of the invention in which rubber bands 17 from openings 18 form a distorted triangular arrangement around the pin opening 2, and whereby the bands from the said openings 18 extend through the pin opening 2 in a diagonal relation to provide friction members which will engage the turntable pin and thus hold the record in position on the table while the record is being played.

20 From the foregoing, it will be observed that the several forms of the present invention each provide resilient live rubber contact means, preferably from a live rubber band arrangement, which rubber is adapted 25 to cooperate with the record table pin to hold the record in position while playing, and at the same time obviate the difficulties which arise in case the pin opening in the record tends to wear.

30 The several rubber bands preferably, though not necessarily, are under slight tension in order to cause the bands to lay flat on the side of the phonograph record.

Having described my invention, I claim:

35 1. A phonograph record of the disc type provided with a pin opening located in the center thereof, and friction bands extending through said opening and anchored to said phonograph record.

40 2. A phonograph record of the disc type provided with a pin opening in the center thereof, and a plurality of flexible rubber bands extending through said pin opening to comprise a friction member adapted to 45 engage the pin of a record table.

3. A phonograph record of the flexible disc type comprising a circular body provided with a central pin opening therein, and a plurality of flexible bands anchored to said 50 record and extending over a portion of said pin opening whereby said bands are adapted to engage a record table pin to retain said record in place on said table when said record is in use.

55 4. A phonograph record of the flexible disc type provided with a centrally located pin opening, and a plurality of looped resilient rubber bands looped through said opening to comprise resilient friction members.

60 5. A phonograph record of the disc type having a centrally located pin opening, and a plurality of rubber bands under tension anchored to said record and having a portion thereof positioned relative to said opening in 65 such manner as to engage the side of a record

table pin when said phonograph record is in playing position on the record table.

6. A phonograph record of the flat disc type provided with a central pin opening, and a plurality of rubber bands carried by said phonograph record and having portions of said bands nearer to the center of the record than the side walls of said opening whereby said bands contact with a record table to retain said record in place on a record turntable when the record is in use.

7. A phonograph record of the flexible disc type provided with a pin opening and a plurality of rubber band members mounted on both sides of said record and adapted to contact with a record table pin when said record is in playing position on the record table.

8. A phonograph record of the flexible disc type having a centrally located pin opening, and a plurality of resilient bands carried by said record and adapted to comprise friction members to engage a record turntable pin to retain said record in position on said turntable when said record is in use.

ARTHUR M. ACHESON.
